ELECTRICAL CONDUCTOR RETAINING
DEVICEUlrich C. Dunaway, Richmond Heights, Mo., as-
signor to James R. Kearney Corporation,
St. Louis, Mo., a corporation of Missouri

Application January 25, 1939, Serial No. 252,757

5 Claims. (Cl. 248—65)

This invention relates generally to electrical conductor-retaining devices and more specifically to a device of this type which is adapted particularly for use with temporary cross arms and temporary side arms associated with conductor-supporting poles, the predominant object of the invention being to provide a simple device of this type which is of such improved construction and arrangement that it is capable of performing its intended function in an improved and highly efficient manner.

As is quite generally known by persons familiar with such matters permanent cross-arms and side arms associated with poles employed for supporting electrical conductors, periodically are removed from the poles for repairs or replacement, and when this is done temporary cross arms or side arms must be applied to the poles to support the conductors while the work is being done. The temporary cross arms and side arms are provided with conductor-retaining devices which serve to hold the conductors in their proper positions with respect to the temporary cross arms or side arms and with respect to each other, and the prime object of this invention is to provide such a conductor-retaining device which is of such improved construction and arrangement that a conductor may be quickly and easily engaged with or disengaged from the retaining device, and when so engaged will be securely held by the retaining device.

Fig. 1 is a fragmentary side elevation of a pole and temporary side arm assembly illustrating the plurality of the improved conductor-retaining devices associated with the temporary side arm.

Fig. 2 is a plan view of one of the improved conductor-retaining devices, shown in association with a fragment of a temporary side arm and with a portion of a conductor.

Fig. 3 is an enlarged section taken on line 3—3 of Fig. 1 and looking in the direction indicated by the arrow.

Fig. 4 is a section taken on line 4—4 of Fig. 3. In the drawing, wherein is shown for the purpose of illustration, merely, one embodiment of the invention, A designates a conventional pole of the type employed to support overhead electrical conductors. Secured to the pole A is a temporary side arm B, said temporary side arm being made up of a pair of arm members disposed in parallel arrangement and spaced apart from each other as shown in Figs. 2 and 3. The arm members of the temporary side arm are secured together at the outer end of the side arm

by bolts C which pass through said arm members and through a spacer D located between said arm members. At its opposite, or inner, end the temporary side arm is pivotally attached by means of a bolt E to a saddle element F which engages the pole A, and said saddle element is secured to the pole by a chain G which passes about the pole and engages the saddle element. The temporary side arm B is provided with a strut H which is pivotally attached at J to a member K secured to the side arm and engages the pole at its opposite end so as to support the side arm in a substantially horizontal position, the pole-engaging end of the strut being supported by a chain L which is attached to an ear formed on the saddle element F and which is engaged at its opposite end by a buckle M pivotally associated with the strut.

Supported by the temporary side arm B and spaced longitudinally thereof is a plurality of 20 the improved conductor-retaining devices 1 to which the present invention relates, and because the plurality of conductor-retaining devices are duplicates in construction and the same in operation the detailed description of the construction and arrangement of the conductor-retaining devices will be directed to one thereof.

The improved conductor-retaining device 1 includes an upper member 2 which overlies the spaced, parallel arm members of the temporary side arm B as shown to the best advantage in Figs. 2 and 3, said member 2 comprising a flat plate 2' provided with downturned flanges 3 at opposite sides of the flat plate. The lower face of the flat plate of the upper member 2 contacts 30 with and rests upon the upper faces of the spaced, parallel arm members of the side arm B, and the downturned flanges 3 are disposed in contact with, or in close proximity to, the opposed outer faces of the spaced, parallel arm 35 members of the side arm. Extended downwardly from the flat plate 2' of the upper member 2, and preferably formed integral therewith, is a body 4 which is disposed between the spaced, parallel arms of the side arm B, said body 4 being shaped as shown in Figs. 3 and 4. The body 4 has formed vertically therein an opening 5 in which the upper end portion of a rod 6 is disposed, said rod being secured to the body 4 by a transverse pin 7 (Fig. 4) which is disposed in aligned openings formed in the body 4 and in the rod 6. The rod 6 extends downwardly from the body 4 to a point below the lower faces of the spaced, parallel arm members of the side arm 50 55

B, and said rod is externally screwthreaded for a purpose to be hereinafter set forth.

The improved conductor-retaining device includes also a lower member 8 which underlies the spaced, parallel arm members of the side arm B, said lower member 8 comprising a flat plate 8' which contacts with the lower faces of the spaced, parallel arm members of the side arm and having upturned flanges 9 which contact with, or lie in close proximity to, the outer faces of said spaced, parallel arm members of the side arm. The lower member 8 is provided with a body 10 which is disposed between the spaced, parallel arm members of the side arm B, said body 10 being extended upwardly from the plate 8' and being shaped as shown in Figs. 3 and 4. The lower member 8 is provided with an integral lower portion 11 having a convex face, and extended outwardly from this lower portion 11 in opposite directions are integral strengthening ribs 12. The lower member is provided with a vertical opening 13 which passes through the body 10 and lower portion 11, and the rod 6 extends through this opening.

Arranged on the lower screwthreaded portion of the rod 6 is a nut in the form of an internally screwthreaded sleeve 14, said sleeve being provided with an operating arm 15 having a suitable grip 16. The upper face of the sleeve 14 contacts with the convex face of the lower portion 11 of the lower member 8, and obviously rotation of the sleeve in one direction, with the aid of the operating handle 15, will cause the upper member 2 and the lower member 8 to be moved toward each other so that the flat plates of said upper and lower members will engage and grip the top and bottom faces of the spaced, parallel arm members of the temporary side arm. Likewise by rotating the sleeve 14 in the opposite direction the entire conductor-retaining device may be removed from the side arm B, or the gripping engagement of the upper and lower members 2 and 8 with respect to the arm members of the side arm may be relieved to permit adjustment of the conductor-retaining device longitudinally of the side arm B.

Extended upwardly from the flat plate 2' of the upper member 2 is a pair of spaced apart ears 17. The ears are curved when viewed in side elevation as shown to the best advantage in Fig. 1, the inner curved faces of the associated ears providing the ears with alined, semi-circular cavities 17'. Disposed between the ears 17 is a conductor-locking element 18 which is pivoted to said ears by a pivot pin 19 that extends through alined openings formed in the locking element and in the ears, said pivot pin being retained in place by cotter pins located adjacent to the opposite ends of the pivot pin.

The shape of the conductor-locking element 18 is shown to the best advantage in Fig. 4 wherein this element is illustrated as being provided with an extension 18' that extends outwardly and upwardly from the main body portion of the element, said extension being provided with a lower cam face 20 which, in the normal position of the element 18 is inclined outwardly and upwardly as shown in Figs. 1 and 4. The conductor-locking element 18 is shaped so that it is provided with an approximately semicircular cavity 21 which coincides in part with the alined cavities formed in the ears 17; that is to say, when the conductor-locking element 18 is in its normal position, as shown in Figs. 1 and 4, a portion of the wall of the cavity 21 of said element is alined and coin-

cides with portions of the walls of the cavities of the ears 17.

Wound about the pivot pin 19 is a torsional coil spring 22 which tends to move the conductor-locking element 18 to its normal position as shown in Fig. 4. As shown in Figs. 2 and 3 the opposite side faces of the conductor-locking element 18 are spaced from the inner faces of the ears 17 and coiled portions of the torsional coil spring 22 surround the pivot pin 19 in these spaces. The coiled portions of the torsional coil spring 22 which are disposed in the spaces between the conductor-locking element 18 and the ears 17 are joined by a bridge portion 23 of the spring and this bridge portion 23 engages beneath a shoulder 24 formed on the conductor-locking element 18 as shown in Figs. 3 and 4. The opposite ends of the torsional coil spring contact with the flat plate 2' of the upper member 2 as shown at 24' in Figs. 2, 3, and 4. The extension 18' of the conductor-locking element is provided at its outer end with an aperture 25, and said conductor-locking element is provided with ribs 26 which serve to provide the element with the required strength and rigidity. Also the conductor-locking element 18 is provided with a nose portion 27 which, when said element is in its normal position, contacts with an inclined face 28 formed on the upper member 2 to arrest movement of said conductor-locking element in response to force exerted by the torsional coil spring 22.

In the use of the improved conductor-retaining device disclosed herein as many devices as may be required are applied to a temporary side arm as shown in Fig. 1, or to a temporary cross arm. The temporary arm is then secured to a pole immediately adjacent to a side arm or cross arm which is to be repaired or replaced, and the conductors are detached from the permanent arm and with the aid of suitable hot line tools are moved to positions where each thereof is in the position of the conductor X shown in Fig. 1. The lineman, who is supported on the pole, then pushes the conductor along the temporary arm toward the adjacent conductor-retaining device, with the aid of a suitable insulated tool and as the conductor is moved against the inclined face 20 of the conductor-locking element 18 of the conductor-retaining device the free end portion of said element 18 is cammed upwardly against the action of the torsional coil spring 22. As movement of the conductor is continued it will pass inwardly of the nose portion 27 of the conductor-locking element, thereby permitting the torsional coil spring to return the conductor locking element to its normal position where the conductor is locked in the associated cavities of the conductor-locking element 18 and the ears 17 as shown at the right hand end of Fig. 1. When a conductor is to be released from one of the improved conductor-retaining devices a suitable tool is introduced into the aperture 25 of the conductor-locking element and the free end of this element is elevated a sufficient distance to permit movement of the conductor out of the cavities of the ears and away from the conductor retaining device. The conductor may then be handled by suitable tools to replace it in association with a permanent arm of the pole.

I claim:

1. In combination, an arm of a pole, and an electrical conductor-retaining device, said electrical conductor-retaining device comprising a member fixed to said arm and provided with a conductor-receiving cavity, a conductor-locking

5 element pivotally supported by said member, and a cam face on said conductor-locking element, said cam face being so related to a surface of said arm that a conductor supported by said surface of said arm and moved slidingly therealong will move against said cam face to cam said conductor-locking element to a position where the conductor may move into said conductor-receiving cavity of said member, said conductor-locking element being movable when the conductor has been moved into the conductor-receiving cavity of said member to a position where the conductor is locked thereby in said conductor-receiving cavity of said member.

10

15 2. In combination, an arm of a pole, and an electrical conductor-retaining device, said electrical conductor-retaining device comprising a member fixed to said arm and provided with a conductor-receiving cavity, a conductor-locking element pivotally supported by said member, a cam face on said conductor-locking element, said cam face being so related to a surface of said arm that a conductor supported by said surface of said arm and moved slidingly therealong will move against said cam face to cam said conductor-locking element to a position where the conductor may move into said conductor-receiving cavity of said member, said conductor-locking element being movable when the conductor has 25 been moved into the conductor-receiving cavity of said member to a position where the conductor is locked thereby in said conductor-receiving cavity of said member, and spring means which 30 tends to move said conductor-locking element 35 to the conductor locking position.

3. In combination, an arm of a pole, and an electrical conductor-retaining device, said electrical conductor-retaining device comprising a member fixed to said arm and provided with a conductor-receiving cavity, a conductor-locking element pivotally supported by said member and provided with a conductor-receiving cavity which normally cooperates with the conductor-receiving cavity of said member to provide an enclosed conductor-retaining cavity, and a cam face on said conductor-locking element, said cam face being so related to a surface of said arm that a conductor supported by said surface of said arm and moved slidably therealong will move against said cam face to cam said conductor-locking element to a position where the conductor may move into said conductor-receiving cavity of said member, said conductor-locking element being movable when the conductor has been moved into the conductor-receiving cavity of said member to a position where the conductor is locked thereby in the enclosed conductor-retaining cavity provided by the cooperating cavities of said member and said element.

4. In combination, an arm of a pole, and an electrical conductor-retaining device, said electrical conductor-retaining device comprising a member fixed to said arm and provided with a conductor-receiving cavity, an inclined surface formed on said member which leads to the conductor-receiving cavity thereof, a conductor-locking element pivotally supported by said member and provided with a conductor-receiving cavity which normally cooperates with the conductor-receiving cavity of said member to provide an enclosed conductor-receiving cavity, and a cam face on said conductor-locking element, said cam face being so related to a surface of said arm that a conductor supported by said surface of said arm and moved slidingly therealong will move against said cam face to cam said conductor-locking element to a position where the conductor may move into said conductor-receiving cavity of said member, said conductor-locking element being movable when the conductor has been moved into the conductor-receiving cavity of said member to a position where the conductor is locked thereby in the enclosed conductor-retaining cavity provided by the cooperating cavities of said member and said element. 5 10 15 20 25

5. In combination, an arm of a pole, and an electrical conductor-retaining device, said electrical conductor-retaining device comprising a member fixed to said arm and provided with a conductor-receiving cavity, an inclined surface formed on said member which leads to the conductor-receiving cavity thereof, a conductor-locking element pivotally supported by said member and provided with a conductor-receiving cavity which normally cooperates with the conductor-receiving cavity of said member to provide an enclosed conductor-retaining cavity, a cam face on said conductor-locking element, said cam face being so related to a surface of said arm that a conductor supported by said surface of said arm and moved slidingly therealong will move against said cam face to cam said conductor-locking element to a position where the conductor may move into said conductor-receiving cavity of said member, said conductor-locking element being movable when the conductor has been moved into the conductor-receiving cavity of said member to a position where the conductor is locked thereby in the enclosed conductor-retaining cavity provided by the cooperating cavities of said member and said element, spring means which tends to move said conductor-locking element to the conductor-locking position, and securing means for fixing said member to said arm.

ULRICH C. DUNAWAY.
